Elimir J. Ney, of Lowell, Mass.
Assignor to
Lowell Manufacturing Co.
Letters Patent No 1300, dated Aug. 7, 1860.

The schedule referred to in these Letters Patent and making part of the same,

To all whom it may concern;

Be it known that I, Elimir J. Ney, of Lowell, in the County of Middlesex, and State of Massachusetts, have originated and designed a new pattern for Carpets, or other fabrics, of which the following, is a full, clear and exact description, of same being had to the accompanying drawings, making part of this Specification.

1. 2. 3 & 4, in the corners are quarters of a figure comprised of four leaves, meeting on the ground. A. B. in the centre is a plain rosette, resting on the square figure 5. Running between the centre and corners are the stair shaped bands C. C. C. C. which surround the ground A.

6 & 7. and 8 & 9. at the sides and ends of the design form small rosettes which overlap the bands C. C. C. C. Extending towards the centre from the bands C. C. C. C. are the sprigs 10, surrounding the ground on which rests the Rosette B. and square 5, are other sprigs 11, extending towards the centre.

The colors employed for the different portions of the design, may be varied to suit the taste and wish of the manufacturer.

Claim,

What I claim as my invention and desire to secure by letters patent, is the design or pattern for Carpets and other fabrics, herein set forth.
